UNITED STATES PATENT OFFICE.

ANNE COLLINS BERRY, OF NEW YORK, N. Y.

GARMENT.

1,382,461.

Specification of Letters Patent. Patented June 21, 1921.

Application filed February 7, 1919. Serial No. 275,618.

To all whom it may concern.

Be it known that I, ANNE COLLINS BERRY, a citizen of the United States, and a resident of the city of New York, Elmhurst, borough of Queens, in the county of Queens and State of New York, have invented a new and Improved Garment, of which the following is a full, clear, and exact description.

The invention relates to children's and ladies' garments, such, for instance, as shown and described in the application for Letters Patent of the United States, No. 81,297, filed by me on February 29, 1916.

The object of the invention is to provide certain new and useful improvements in outer or undergarments having legs, such as rompers, bloomers, drawers, combination chemise and drawers, and the like, and whereby the desired comfort to the wearer is insured, and the wearer can readily exercise the lower limbs in walking, running, or jumping without being unduly hindered by the garment. Another object is to render the garment exceedingly strong and durable especially at the crotch and to allow convenient opening at the crotch, and leg sides for sanitary and other purposes.

With these and other objects in view, the invention consists of certain novel features of construction as hereinafter shown and described and then specifically pointed out in the claim.

A practical embodiment of the invention is represented in the accompanying drawings forming a part of this specification, in which similar characters of reference indicate corresponding parts in all the views.

Figure 1 is a front elevation of the improved garment in the form of rompers;

Fig. 2 is an inverted plan view of the same with one of the legs partly opened;

Fig. 3 is an enlarged cross section of the same on the line 3—3 of Fig. 1;

Fig. 4 is a front elevation of the improved garment in the form of a combination chemise and drawers;

Fig. 5 is an inverted plan view of the same with one of the legs partly opened; and

Fig. 6 is an enlarged cross section of the same on the line 6—6 of Fig. 4.

The garment shown in Figs. 1, 2 and 3 is in the form of rompers and comprises a body 10 having a neck opening 11, collar 12, sleeves 13, and legs 14 and 15. In practice, the body 10 is preferably made from a single piece of

material doubled up across the shoulders and fastened together along the under sides of the sleeves and the sides to produce the body 10. The legs 14 and 15 are provided with 60 hems 16 and 17 containing elastic bands fastened at the ends to the hems to gather the latter with a view to fit the hems snugly around the thighs of the wearer's legs. An opening is formed at the bottom of the garment extending sidewise from the inner side of the leg 14 across the crotch 20 to the inner side of the other leg 15, and this opening has its walls formed of two strips or flaps 21 and 22 of a doubled-up fabric material, preferably straight-cut and sewed to the edges of the opening. The strip 21 extends over the top of the strip 22 when the strips are in closed position, as plainly indicated in the drawings, the ends of the strips being fastened to the ends of the corresponding hems 16 and 17, as plainly shown in Fig. 2. The strips 21 and 22 are adapted to be fastened together and for this purpose the uppermost strip 21 is preferably provided at its under 70 side with buttons 25 adapted to engage buttonholes 26 formed transversely in the bottom strip 22 to securely fasten the strips or flaps 21 and 22 together. It is understood that I do not limit myself to the particular 85 fastening described as the same may be varied without deviating from my invention. Two of the buttons and corresponding buttonholes 25 and 26 are located at the legs 14 and 15 and one button and its buttonhole 90 are arranged at the middle of the strips and hence when the two strips are overlapped as described and fastened together they securely close the opening which extends from one leg to the other. 95

It will be noticed that by the arrangement described the two closing strips 21 and 22 strongly reinforce the body of the garment at the bottom from one leg to the other, and the strips can be readily opened for donning 100 or for taking off the garment or for sanitary purposes, etc.

It will also be noticed that by arranging the strips one on top of the other an exceedingly smooth joint is provided between 105 the front and rear portions of the garment and hence this joint is not liable to chafe.

It will further be noticed that by the arrangement described the wearer has complete freedom of the lower limbs thus rendering 110 the garment exceedingly serviceable as a romper, bloomer or the like.

For a combination chemise and drawers, as shown in Figs. 4, 5, and 6, the two closing strips or flaps 40 and 41 are formed by doubling up the free edges of two pieces 42 and 43 of a material sewed at its outer edges to the body 44 of the garment, the said pieces 42 and 43 forming portions of the legs 45 and 46 and the crotch of the body 44. In this case the hems and elastics are dispensed with but the flaps 40 and 41 are adapted to be fastened together by fastening devices such as buttons and buttonholes 50 and 51 in the same manner as above described in reference to the garment shown in Figs. 1, 2 and 3. It is understood that in this garment a looseness is desired at the legs and the crotch and consequently the strips or

flaps 40, 41 are formed of the pieces 42 and 43 to give the desired looseness to the under side of the garment at the crotch and the legs.

Having thus described my invention, I claim as new and desire to secure by Letters Patent:—

A garment comprising a body having leg openings and a straight cut from the leg openings into the body, leaving edges at the front and the rear; finishing pieces attached to the respective edges and laid in horizontal relationship transversely of the crotch to easily enable the pieces to fall into an inverted V-shape; and complementary fastening means on the pieces.

ANNE COLLINS BERRY.
